UNITED STATES PATENT OFFICE.

ERNEST UNGER, OF BROOKLYN, NEW YORK.

ELECTRIC HEATER.

Application filed July 21, 1927. Serial No. 207,558.

The invention relates to an electric heater constituting part of the apparatus used in practicing the art of waving hair on a person's head in the so-called permanent hair waving treatment. The primary object of the invention is to provide a simplified form of electric heater of the hollow tube type now in general use and which can be manufactured and marketed at a cost less than the present market price of similar forms of heaters.

Accordingly, the invention features simplicity in construction of such a heater, the forming of the parts as far as possible from drawn tubing and stamping, the minimizing in the number and formation of component parts and the providing of means for securing the parts without necessity of providing fastening means other than the structural parts necessary to form the heater.

Another object is to provide a heater of the type outlined which can be conveniently manipulated and in which the usual supporting electric leads may be utilized in connection with an insulating knob of small dimension to adjust the heater as a whole while in use.

Still another object of the invention is to provide as part of the heater an improved form of readily removable closing cap which will provide for the requisite amount of steam leakage from the heater, which will assist in locating a contained curling stick or rod, which will act to center the rod in the tube and when removed from the tube will provide free access to the tube and cap to permit cleaning of the same.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawing,

Fig. 1 is a view partially in side elevation of an electric heater constituting a preferred embodiment of the invention and partially in axial section.

Fig. 2 is a transverse sectional view taken on the plane indicated by the line 2-2 of

Fig. 1 and looking in the direction indicated by the arrows; and

Fig. 3 is a transverse sectional view of the cap and taken on the line 3-3 of Fig. 1.

In the drawings, there is shown a relatively long inner tube 10 opened at opposite ends and having a straight, uniform bore 11 for containing the strands of hair wrapped on a curling rod (not shown) as is usual and well known in similar structures. Encircling the portion of the tube 10 adjacent one end 12 is a relatively short frusto-conical outer shell 13 providing, between the shell and the inner tube, a heating space 14 containing the usual electric windings 15. The end 12 of the inner tube is spun over the smaller end 16 of the outer shell so as to provide a waterproof lap joint therebetween. The opposite, larger end 17 of the outer shell is closed by means of an end plate 18 which encircles the inner tube 10 and is provided with a flange or shoulder 19 telescoping into the outer shell. Externally of the end plate, the inner tube is formed with a bead 20 which laps the end plate and prevents movement of the end plate away from the outer shell. The outer shell and the flange 19 are provided with interlocking depressions or notches 21 which act to prevent relative rotary movement between the end plate and the outer shell.

The opposite or rear end of the inner tube 11 is externally screw threaded as shown at 22 and is engaged by a screw cap 23. The cap is formed of two parts, a tubular metal part 24 and a disc like flat bakelite knob 25. The metal tubular part 24 includes in order from left to right of the showing in Fig. 1, a cylindrical sleeve 26 internally threaded and adapted to engage the threads 22 on the inner tube. Next in order, the cap is formed with a reinforcing bead 27 which merges into the larger end of a frusto-conical rod guiding portion 28 and this in turn has its smaller end distended to form a small tubular portion 29, the outer end of which is upset to form an outwardly extending annular fastening flange 30 for securing the knob 25 in place. In order to prevent rotary movement of the knob on the tube 29, the rear portion of the knob is provided with a boss 31 and the portion of the tube extending through its bore is formed non-circular in outline, in the instant case shown to be hexagonal as indi-

cated at 32, Fig. 3. The portion of the tube 29 beyond the hexagonal portion is circular in outline to provide a centering means 33 for engaging the usual curling stick to center the 5 same axially in the tube 10.

The knob 25 is of moulded bakelite or similar heat insulating material, is of greater diameter than the cylindrical portion 26 of the cap and has its outer edge milled as indicated at 34 whereby the knob can be conveniently gripped without the operator's fingers coming in contact with the hot metal portion of the cap.

A strap 35 encircles the inner tube adjacent to its threaded end and between this threaded end and the outer shell. The strap is adjustably fastened in position on the shell by means of a small screw and nut form of clamp 36. The upper free ends of the 20 strap 35 are bent about a groove 37 formed about the outer sides of a cylindrical spool-like sleeve 38 formed of insulating material. The strap is held against rotary movement on the shell by means of a notch 39 in the 25 inner tube projecting between the ends of the strap 35 as particularly shown in Fig. 2. The sleeve is provided with an axially extending bore 40 through which is passed electric leads 41 which extend therethrough, along the portion of the tube 10 between the same and the end plate, through lead apertures 42 in the end plate which are in substantial alignment with the bore 40. The ends of the leads intruded through the end 30 plate 18 are connected electrically to the winding 15 within the outer shell.

It is readily appreciated that the several parts of the structure as thus described can be cheaply constructed in large quantities as 40 a factory production. The several parts can be readily drawn and stamped to shape and except for the threading of the flat end tube refined machine operation is reduced to a minimum. Positioning the insulating sleeve 45 and the electric leads extending therethrough adjacent the heat insulating knob permits

the operator to hold the heater even when hot by means of the leads and knob and there has thus been avoided the burning of the operator which heretofore has frequently resulted with other similar forms of heaters. Securing the electric leads directly to the heater and in spaced relation to their connections with the windings in the outer shell tends to transfer strain between the leads and the heater to the insulating sleeve and its holding strap and this tends to minimize the possibility of breakage between the electric leads and the windings in the outer shell.

The cap normally remains in position in threaded engagement with the inner tube but may be readily unscrewed so as to permit access to the interior of both the tube and cap for the purpose of cleaning the same. The construction disclosed features the hermetic sealing of the heater winding so that the windings are protected while in use and while the structure is being cleaned.

I claim—

1. A cap including a one piece metal tube fashioned to form in order from one end, a cylindrical portion, a bead, a frusto-conical portion and a tube non-circular in cross section, an apertured knob with the non-circular tube extending through its aperture and said tube acting to hold the knob from relative rotary movement and the outer end of said tube being spun over to secure the knob in place.

2. An electric heater comprising a long metal tube opened at both ends and with one end exteriorly threaded, a screw cap in engagement with the threaded end and provided axially of the bore of the tube with an aperture, said cap provided with a knob formed of insulating material for handling the heater as a whole.

Signed at New York, in the county of New York, and State of New York, this seventh day of July, A. D. 1927.

ERNEST UNGER.
